D. HEUSINKVELD.
SUSPENSION RAFTER AND SUPPORT.
FILED AUG. 3, 1921.

UNITED STATES PATENT OFFICE.

DERK HEUSINKVELD, OF HULL, IOWA.

SUSPENSION RAFTER AND SUPPORT.

Application filed August 3, 1921. Serial No. 489,583.

To all whom it may concern:

Be it known that I, DERK HEUSINKVELD, a citizen of the United States, and a resident of Hull, in the county of Sioux and State of Iowa, have invented a new and Improved Suspension Rafter and Support, of which the following is a full, clear, and exact description.

The present invention relates to new and useful improvements in building appliances and hardware, and it pertains more particularly to means for bracing the joints of the rafters of hip roofs.

It is one of the primary objects of the invention to provide means by which the rafters of a hip roof may be secured together at their joints without the use of nails or similar fastenings, except to prevent relative movement of the members at the joint.

It is a further object of the invention to provide means by which the joint may be tightened from time to time as conditions require.

It is a further object of the invention to so construct a device of this character that it is applicable to hip roofs regardless of the angle of the rafters.

It is a still further object of the invention to so construct a device of this character as to render the same adjustable to angles of rafters of varying degrees.

With the above and other objects in view, reference is had to the accompanying drawings, in which—

Figure 1 is a side elevation of the joint of the rafters of a hip roof showing the improved device and its method of application in actual practice.

Fig. 2 is a vertical sectional view taken on the line 2—2 of Fig. 1, and showing the device in rear elevation, a portion of one of the members of the device being broken away.

Referring more particularly to the drawings, the reference character 5 designates the vertical rafter, and 6 designates the horizontal rafter of a hip roof. It is to be understood that the roof is supported by these rafters and that there are a sufficient number thereof to provide a proper support for the roof.

Secured to the rafter 5 upon opposite sides thereof, by means of a bolt or the like 7, are straps 8, and said straps 8 are adapted to extend inwardly of the rafter in a substantially horizontal plane.

Secured to each of the rafters 6 by means of a bolt 9 or the like, are oppositely-disposed depending straps 10, and said straps 10 depend adjacent their corresponding strap 8 and have their free end lying in juxtaposition to the inner free end of their respective free strap 8, as more clearly shown in Fig. 1. Extending through the free ends of the straps 8 and 10 is a single bolt 12, and surrounding said bolt 12 is a tubular sleeve 13, by means of which the straps 8 and 10 are prevented from buckling or bending to such a degree that they would slide along the bolt 12 in either direction.

Surrounding the sleeve 13 is a link 14, and pivotally connected in said link 14, is a screw-threaded eye bolt 15, a nut 16 having engagement with the threaded end 17 of said eye bolt 15. The reference character 20 designates a rigid angular member, and in use two of these members are employed. Each of these members is provided in the free ends of its legs, with a series of openings 21, and said openings are adapted to receive bolts 22, by means of which the rigid angular members are secured to the rafters 5 and 6. These angular members are connected at their apexes by a transversely extending rigid member 23. The angular members 20 and the transverse rigid member 23 are preferably formed of angle iron and the rigid member 23 is secured to the angular members by means of bolts or the like 24. The transverse rigid member 23 is adapted to receive the threaded end of the eye bolt 15 as indicated by the reference character 30 in Fig. 1, and the nut 16 is adapted to engage the transverse rigid member 23 in order to tighten the eye bolt 15.

The reference character 31 designates a strap or brace which is secured in position by the heretofore mentioned bolts 22, and it will be noted from Fig. 1 that said strap or brace 31 embraces the straps 8 and 9, and prevents bending thereof when the device is being positioned.

The device functions in the following manner:

The members 8 and 10 are secured in position by means of their bolts 7 and 9, respectively, after which the bolt 12 and the sleeve 13 are positioned with respect to these members 8 and 10. After this has been done, the angular members 20 are positioned and the eye bolt is passed through the rigid

transverse member 23, after which the nut 16 is threaded upon the threaded end 17 of the eye bolt 15 and the eye bolt 15 is placed under tension. As the eye bolt 15 is placed under tension, the strain exerted will cause the joint of the rafters 5 and 6 to assume the proper position and said rafters 5 and 6 will be maintained in proper position to support the roof. Simultaneously with the placing of the angular members 20, the straps or braces 31 are positioned to overlap the members 8 and 10, as shown in Fig. 1, and prevent their bending or buckling under the strain exerted by the eye bolt.

15 From the foregoing it is apparent that the present device provides means for supporting and sustaining the rafters of hip roofs without employing driven fastenings, such as nails, and cumbersome vertical braces as is the common practice. Furthermore, the improved device permits of the tightening of the rafter joints from time to time as occasion may require, and provides a means which is adaptable for use with hip roofs of various degrees of angle.

20

25

I claim:

1. In combination with the rafters of a hip roof, a plurality of members rigidly secured to said rafters and extending inwardly thereof, rigid means connecting said members, angular members pivotally secured to the rafters, and tension means connecting the first-mentioned members with the rigid angular members, as and for the purpose set forth.
- 30
- 35
2. In combination with the rafters of a hip roof, a plurality of inwardly-projecting members arranged in triangular form, said members being pivotally secured to the rafters, rigid means connecting said members, a plurality of oppositely disposed angular members pivotally connected to the
- 40

rafters, a rigid member connecting said angular members, and tension means connected to the first-mentioned members and to the triangular members, as and for the purpose set forth.

3. A brace for the rafters of hip roofs, said brace comprising a plurality of members secured to the rafters of the roof in triangular relation, rigid means connecting said members, angular members connected to the rafters of the roof, angularly disposed braces connected to the angular members and overlying the first-mentioned members, rigid means connecting the angular members, and tension means connected to the first-mentioned members and the rigid means connecting the angular members, as and for the purpose set forth.

4. A device of the character described comprising in combination with angularly disposed rafters, a plurality of straps secured to said rafters on opposite sides thereof, said straps being arranged at substantially right angles one to the other, rigid right-angular members secured upon opposite sides of the rafters, tension means connecting the rigid right-angular members with the straps, and braces connected to the rigid right-angular members and overlying said straps, as and for the purpose set forth.

5. A device of the character described comprising a brace for angularly disposed rafters comprising a plurality of straps secured to said rafters on opposite sides thereof, said straps being arranged at an angle one to the other, rigid right-angular members secured on opposite sides of the rafters, and tension means connecting the rigid right-angular members with said straps.

DERK HEUSINKVELD.
